UNITED STATES PATENT OFFICE

171,530

TEXTILE FABRIC

Paul P. Chiarelli, Brooklyn, N. Y., assignor to Chicopee Mills, Inc., a corporation of New York

Application August 13, 1953, Serial No. 26,441

Term of patent 14 years

(Cl. D92—1)

To all whom it may concern:

Be it known that I, Paul P. Chiarelli, a citizen of the United States, residing at Brooklyn, in the county of Kings, State of New York, have invented a new, original, and ornamental Design for a Textile Fabric, of which the following is a specification, reference being had to the accompanying drawing, forming a part thereof, wherein in the figure is a plan view of a textile fabric showing my new design.

I claim:

The ornamental design for a textile fabric, as shown.

PAUL P. CHIARELLI.
